CLOSING OF VALVE BAGS

Alfred Du Bois, Paris, France

Application December 21, 1936, Serial No. 117,057
In France January 22, 1936

8 Claims. (Cl. 229—62.5)

The present invention relates to valve bags and more particularly to bags having a very wide valve, and its object is to improve the closing of said valve so as to obtain a perfect and certain closure, even in the case of powdered products of the most flowing type, such as sand for example, or delicate products such as flour; a further object is to enable, if desired, the closed valve to be readily sealed.

For the above purpose, the valve bag is provided with a closure device for the valve consisting of a member made of cardboard, paper or other similar material fixed to the outer lip of the valve and having outside the bag a free transverse flap preferably of substantially the width of the valve, which flap is arranged so that after filling the bag, it can be folded back and introduced into a kind of pocket formed on the outer face of the inner lip of the valve, having substantially the width of said valve, and of which the opening is turned outwardly.

Three examples of embodiment of the closure device having the above defined characteristic and other advantageous peculiarities are illustrated in the accompanying drawing in which:

Fig. 1 is a partial section of a valve bag through the median plane passing through the axis of the valve and showing the closure device before the valve is closed;

Fig. 2 is a section identical with Fig. 1 but shows the valve closed;

Fig. 3 is a plane view of the bottom of the bag of Figs. 1 and 2;

Fig. 4 is a view similar to Fig. 1 of a modified embodiment;

Figs. 5 and 6 are respectively similar views to Figs. 1 and 2 but showing another modified embodiment.

In the example of embodiment of Figs. 1 and 2, a closure part 1 made of relatively flexible paper, advantageously of creped paper, is fixed to the outer lip 2 of the valve of a bag 3, preferably by means of staples. Said part 1 is extended beyond the staple which is nearest the outer opening of the valve by a part 4 which forms a free transverse flap of substantially the width of the valve. On the other hand, the inner lip 5 of the valve is cut in the angles over a part of its length, from its end within the bag, and the part 7 between said incisions 6 is folded back towards the outer opening of the valve, on the upper side of said inner lip 5, about a line A—B passing through the starting point of said incisions 6. It will be seen that in this manner a kind of pocket having a width substantially equal to that of the valve

and which is open outwardly is formed on the upper face of the inner lip 5 of the valve. Furthermore the large faces 7 and 5 of said kind of pocket are not fixed to each other along their lateral edges.

With a bag thus constructed, the introduction of the filling tube and the filling of the bag are effected as with an ordinary valve bag. When the bag is full and the tube has been withdrawn, it suffices to fold back the flap 4 by hand inside the pocket (Fig. 2) to obtain a hermetically closed valve which it is possible to seal with a staple, a seal or any similar device connecting together the outer part of the flap 4, the face 7 of the pocket and the part of the flap 4 within the pocket. In order to still further improve the closure, the three aforesaid elements can be folded or rolled together, preferably inside the pocket, as shown in Fig. 2.

In the modified embodiment in Fig. 4, the closure device is similar to that of Figs. 1 to 3 with the sole difference that the pocket is formed by the inner lip 5 of the valve and a piece of paper or cardboard 7' covering the upper face of said lip is fixed on the part of said lip adjacent the aperture of the valve inside the bag.

A similar piece of paper or cardboard can also be provided in the case of the pocket of Fig. 1 to reinforce the face 7 of the pocket and this reinforcing element 8 (Figs. 5 and 6) need not be permanently fixed to the bag but can be folded to form a U-shaped member fitting onto the pocket of the valve and not secured thereto by any means. Both in the cases of Figs. 4 and 5, it is further advantageous that the reinforcing element extends beyond the valve until it comes at a short distance from the outer end of the flap 4 (Fig. 5) thereby considerably facilitating the placing in position of the bag on the filling tube and the folding together of the elements 4 and 8.

Of course, the invention is no way limited to the peculiarities of embodiment and to the constructive details described and illustrated which have only been given by way of example. Thus for example the free transverse flap is not necessarily integral with the part fixed to the outer lip of the valve but it can be attached to the latter and can be made of a different material. Similarly the closure part fixed to the outer lip can be fixed on the outer or inner faces of the latter and be of smaller width than that of the valve, and the less perfect closure thus obtained may nevertheless be sufficient with some products.

What I claim is:

1. A valve bag having its inner valve lip provided with two incisions extending from the inner end of said lip towards the outer valve end upon a part of the length of said lip, the lip portion between said incisions being folded back within the valve over the outer face of the non incised lip part about a line transverse to the valve axis, and a sheet like flap carried by the bag and having a foldable part insertable into the space between the non incised and the folded back lip parts to thereby close the valve opening.
2. A valve bag as in claim 1 wherein said incisions are made in the valve corners.
3. A valve bag as in claim 1 further provided with a U-shaped reinforcing member freely fitted over the fold between the folded back lip part and the non incised lip part and having a foldable projection out of the valve beyond the outer edge of said folded back lip part.
4. A valve bag as in claim 1 further provided with a strap of reinforcing foldable material having substantially the same width as the folded back lip part, inserted in the valve and having a hook-like part freely fitted over the fold between the folded back lip part and the non incised lip part, said strap projecting out of the valve beyond the end of said folded back lip part.
5. A valve bag provided with a valve closure consisting in a pocket formed on the outer face of the inner valve lip and at least partially enclosed within the valve, the inner end of said pocket being closed while its outer end is open as also its lateral sides within the valve, along at least a part of the length of said inner valve lip i. e. the outer pocket wall forms a flap free within the valve, and a sheet-like member carried by the bag within the valve at least the fraction of said member adjacent the outer valve end is free within the valve, i. e. not adhered to the inner face of the outer valve lip but capable of being moved away from said lip to be rolled or tucked into the pocket and within the valve together with said free part of the outer pocket wall to thereby close the valve passageway, said sheet-like flap being made of a sheet of supple paper while the outer pocket wall includes a sheet of strong material like card-board or strong paper.
6. In a valve bag provided with valve closing means including a pocket formed on the outer face of the inner valve lip, the inner end of said pocket being closed while the outer end is open, and a flat foldable member a part of which is provided within the valve passageway and adhered to the bag bottom and the remaining portion of said member projects out of the valve to be insertable into said pocket, said flat foldable member consisting in a sheet-like flap free of connection with said inner valve lip.
7. In a valve bag provided with valve closing means including a pocket formed on the outer face of the inner valve lip, the inner end of said pocket being closed while the outer end is open, and a flat foldable member a part of which is provided within the valve passageway and adhered to the bag bottom and the remaining portion of said member projects out of the valve to be insertable into said pocket, said flat foldable member consisting in a sheet-like flap free of connection with said inner valve lip and adhered to the bottom solely in a region remote from the outer valve end, whereby the part of said member which is located within the valve passageway has its portion adjacent the outer valve end quite free within the valve passageway, and said pocket being laterally open in the valve corners along at least a part of the length of said inner valve lip, i. e. the outer pocket wall forms a flap free within the valve passageway, whereby both said foldable member and outer pocket wall are capable of being rolled or tucked together within the valve passageway.
8. In a valve bag provided with valve closing means including a pocket formed on the outer face of the inner valve lip, the inner end of said pocket being closed while the outer end is open, and a flat foldable member a part of which is provided within the valve passageway and adhered to the bag bottom and the remaining portion of said member projects out of the valve to be insertable into said pocket, said flat foldable member consisting in a sheet-like flap free of connection with said inner valve lip, and the inner valve lip being much shorter than the outer valve lip.

ALFRED DU BOIS.
